UNITED STATES PATENT OFFICE.

LIBORIUS SENGE, OF CRESCENT SPRINGS, KENTUCKY, ASSIGNOR TO THE GLOBE-WERNICKE COMPANY, OF CINCINNATI, OHIO, A CORPORATION OF OHIO.

DRAWER OR SLIDE EQUALIZER.

SPECIFICATION forming part of Letters Patent No. 781,561, dated January 31, 1905.

Application filed October 10, 1904. Serial No. 227,839.

To all whom it may concern:

Be it known that I, LIBORIUS SENGE, a citizen of the United States, residing at Crescent Springs, in the county of Kenton and State of Kentucky, have invented certain new and useful Improvements in Drawer or Slide Equalizers, of which the following is a full, clear, and exact description, reference being had to the accompanying drawings, forming part of this specification.

This invention relates to a new and useful device for equalizing the movement of drawers, slide-doors, desk-shelves, and the like; and the same consists in the combination and arrangement of parts hereinafter described.

The objects of the invention are, first, to furnish a device which will prevent a drawer, door, or slide which moves horizontally into and out of its case from binding and cause both ends to move uniformly; second, to simplify and cheapen the construction of equalizing devices of this character, and, third, to so arrange the equalizing devices that they will give the greatest area or capacity possible in compartments in which they are fitted, as in bookcase units, to permit taller books to be placed in such compartments than could be if equalizing devices of old and well-known kinds somewhat resembling mine were used.

The novelty of my invention will be hereinafter more fully set forth, and specifically pointed out in the claim.

In the accompanying drawings, Figure 1 is a partially-broken plan view of a well-known form of bookcase unit with the slide-door raised and partly pushed in. Fig. 2 is a sectional side elevation of Fig. 1 on the dotted lines $\alpha\alpha$ and looking to the left. Fig. 3 is a sectional elevation on the dotted line yy of Fig. 1 looking to the right.

The same numerals of reference are used to indicate identical parts in all the figures.

In the drawings is shown a single bookcase unit of well-known construction, of which 1 represents the end walls; 2, the back wall; 3

4, the interlocking top and bottom pieces connecting the end walls, and 5 the swinging and sliding door, which is usually a glass-filled frame adapted to entirely close the front opening of the unit when let down and which can be raised or swung up on a pivot and pushed back into the top of the case to give free access to the interior of the unit.

Extending through eyes 6, which may be ordinary screw-eyes secured to the upper edge 7 of the door-frame, are the slightly-curved outer ends of two lever-arms 8 and 9. These are loosely pivoted together at their middle, as at 10, and the arm 8 is pivoted as high up as possible to a bracket-piece 11, secured to the inner side of the rear wall 2, as seen in Fig. 1, while the inner end of the opposite arm 9 is curved and passes through an eye-guide 12, as high up as possible on the rear wall 2 of the unit. This construction brings the arms 8 and 9 as high up in the unit as possible and at the same time forms a perfect equalizing device, and the edge of the door when raised rests and rides upon a roller 13, secured to the inner side of each end wall of the unit, near its front end, a suitable stop 14 being provided on the door-frame to prevent its being pulled too far out and to serve as pivots upon which the door can be let down to its closed position. (Shown in Fig. 3.)

By this simple construction I provide equalizer mechanism which is cheap and thoroughly efficient in its action and which permits the greatest amount of space in each unit to be utilized.

Having thus fully described my invention, I claim—

In a drawer or slide equalizer, the combination with a case, of a sliding hinged door or drawer adapted to cover the open front of the case when drawn out and lowered and to be raised and pushed back into the top of the case to give free access to the same, cross-bars pivoted at or near their middle and having their forward ends slidably connected to

the top edge of the door at each side, and having their rear ends, the one of them stationarily pivoted to the back of the case and the other slidably connected to the back of the case, the connections of the cross-bars with the door and case at their ends being substantially opposite each other and located at the

extreme top of the case, substantially as described.

LIBORIUS SENGE.
